UNITED STATES PATENT OFFICE.

EMIL HUNZIKER, OF JERSEY CITY, NEW JERSEY.

DESIGN FOR WATCH-CROWNS.

SPECIFICATION forming part of Design No. 11,689, dated March 16, 1880.

Application filed February 4, 1880. Term of patent 14 years.

To all whom it may concern:

Be it known that I, EMIL HUNZIKER, of Jersey City, in the county of Hudson and State of New Jersey, have invented a Design for 5 Crowns for Stems of Stem-Winding Watches or Pressure-Stem Watches, of which the following is a specification.

The nature of my design is represented in the accompanying drawings.

10 Figure 1 is a side elevation of the crown. Fig. 2 is a plan of the same with a plain center, and Fig. 3 is a plan of the same with an ornamental center.

15 Similar letters of reference indicate corresponding parts.

Heretofore crowns for stem-winding and pressure-stem watches have ordinarily been made with peripheral vertical grooves extending from the top to the under side of the crown.

20 The leading feature of my design consists in spiral peripheral grooves extending from the top to the under side of the crown, as shown in the drawings.

A is the hollow stem of the crown, designed 25 to fit upon the stem of the watch. B is the rounded head of the crown, whose center is slightly raised, and outlined and defined by a deeply-indented circle or groove, from the edge of which circle to the under lower edge of the

30 crown extend spiral grooves a.

The center b of the crown, which is inclosed

in the circular groove c, projects upward slightly, and may be plain, as shown in Fig. 2, or ornamented with a star, d, as shown in Fig. 3, or have any other suitable design.

I claim as my design and desire to secure 35 by Letters Patent—

1. The design for a crown for a stem-winding or pressure-stem watch herein shown and described, the same consisting of the spiral 40 grooves a a, extending from the top to the under side of the crown.

2. The design for a crown for a stem-winding watch herein shown and described, the same consisting of the spiral grooves a a on 45 the head of the crown, in combination with the circular groove c.

3. The design for a crown for a stem-winding or pressure-stem watch, as herein shown and described, consisting of spiral grooves a 50 a, the circular groove c, and raised center b combined.

4. The design for a crown for a stem-winding or pressure-stem watch, as herein shown and described, and consisting of the spiral 55 grooves a a on the head of the crown, the circular groove c, and ornamental center d combined.

EMIL HUNZIKER.
